UNITED STATES PATENT OFFICE.

JOHN EMORY SCOTT, OF BALTIMORE, MARYLAND.

DESIGN FOR A STAIR-ROD.

SPECIFICATION forming part of Design No. 12,677, dated January 10, 1882.

Application filed December 9, 1881. Term of patent 7 years.

To all whom it may concern:

Be it known that I, J. E. SCOTT, of Baltimore, in the county of Baltimore and State of Maryland, have invented a new and Improved 5 Design for Stair-Rods, of which the following is a full, clear, and exact description.

Reference is to be had to the accompanying drawings, forming part of this specification, in which similar letters of reference indicate corresponding parts in both the figures.

Figure 1 is a side view, and Fig. 2 a cross-section, of my newly-designed rod. A is the rod, the length of which will vary as required. The rod is of triangular shape in cross section, with one side rounded preferably, as shown in Fig. 2, and of gradually-decreasing cross-sectional area from its mid-length toward the ends, so that the two angles seen from the front taper in both directions, while 15 the third angle is on a straight line, in order to fit snugly in the angle of the stairs. The ends of the rod are finished with acorns *a* or

other ornamental device. The rod may be made of wood or metal, and the outer face ornamented. At *c* is a hole for a screw, by which 25 the rod is secured in the angle of the stairs. One or more screws will be used in any desired manner.

Having thus described my invention, I claim as new and desire to secure by Letters Patent— 30

1. The design for stair-rod hereinbefore shown and described, which consists in the triangular cross-sectional form of the rod. 35
2. The design for stair-rod hereinbefore shown and described, which consists in the triangular rod tapering toward the ends.
3. The design for stair-rod hereinbefore shown and described, which consists in the triangular rod with ornamented ends *a*.

JOHN EMORY SCOTT.
